UNITED STATES PATENT OFFICE.

THOMAS J. HALSTEAD, OF DALLAS, TEXAS.

TRACE-LOCK.

SPECIFICATION forming part of Letters Patent No. 659,063, dated October 2, 1900.

Application filed June 16, 1900. Serial No. 20,561. (No model.)

To all whom it may concern:

Be it known that I, THOMAS J. HALSTEAD, a citizen of the United States, and a resident of Dallas, in the county of Dallas and State 5 of Texas, have invented a new and Improved Trace-Lock, of which the following is a full, clear, and exact description.

The purpose of the invention is to provide a trace-lock consisting of a ferrule adapted 10 for attachment to a whiffletree and a button carried by the ferrule, which button can be placed and held in either a horizontal or a vertical position and be operated by one hand as readily in the dark as in the light.

15 The invention consists in the novel construction and combination of the several parts, as will be hereinafter fully set forth, and pointed out in the claims.

Reference is to be had to the accompanying 20 drawings, forming a part of this specification, in which similar characters of reference indicate corresponding parts in all the figures.

Figure 1 is a perspective view of one end 25 of a whiffletree having the improved lock applied and illustrating a trace as locked to the whiffletree by the improved device. Fig. 2 is a vertical longitudinal section through the device and the trace, the parts of the lock being in the locking position shown in Fig. 1; 30 and Fig. 3 is a view similar to Fig. 2, the button of the lock being horizontally placed to permit a trace to be carried from or be placed in connection with the whiffletree.

A represents a portion of a whiffletree, an 35 end of which is fitted with and secured in a ferrule B, and said ferrule may be of an ornamental character, if desired. This ferrule at its outer or closed end is provided with a bifurcated projection or extension B', the upper

40 and lower surfaces of which are flat and the side surfaces more or less tapered, so that the bifurcated extension is of slightly less dimensions transversely at its outer end than where it connects with the ferrule. A pin 11

45 is passed across the space between the members 10 of the bifurcated extension B', and this pin is secured in said members in any suitable or approved manner. The inner wall 12 of the space between the members B' is concaved to a greater or a less extent, as shown in Figs. 2 and 3.

The second portion of the lock consists of

a button D, and this button comprises a tubular shell or casing 14, permanently closed at one end, which permanently-closed end 17 is convexed and is adapted to fit in the concavity 12 of the bifurcated extension B'. The other end of the shell or casing 14 is closed by a block 15, and the sides of the button are open from the block to the end 17. The pin 60 55 11 in the bifurcated extension B' is passed through these side slots in the casing, so that the button is centrally pivoted in the said extension B' of the ferrule B, and a spring 16 is located within the said casing or shell, having bearing on the permanently-closed end 65 17 and against the pin 11.

When a trace is to be placed in connection with a whiffletree, the permanently-closed end 17 of the button is pressed in direction of the 70 pivot-pin 11, thereby contracting the spring 16, whereupon the button may be turned upon its pivot and the end 17 of the button may be made to engage with the concaved wall 12 in the bifurcated extension, as shown in Fig. 75 3, whereupon the button is held by the spring and its frictional engagement with the said wall 12 in a horizontal position, and the eye of the trace C may be readily passed over the button and onto the ferrule extension B', 80 whereupon the button is turned so as to disengage the end 17 from the wall 12, and when the button assumes the vertical position shown in Figs. 1 and 2 it is held in such position by the spring, which expands, and the 85 trace is prevented from coming off from the whiffletree. The inclination of the bifurcated extension B' tends to keep the trace close up against the button D. When the trace is to be removed, the button D is again brought 90 to its horizontal position.

It is obvious that the button may be manipulated in the dark as readily as in the light and that the entire lock is simple, effective, and durable.

Having thus described my invention, I claim as new and desire to secure by Letters Patent—

1. A trace-lock, comprising a trace-receiving section having a forked end, the inner 100 wall between the members of the fork being concaved, a button pivotally and slidably mounted between the members of the fork and having one convexed end adapted to en-

gage the concave wall between the members of the fork, and a spring carried by the button and serving to hold the same in alinement with the trace-carrying section or at right angles thereto, substantially as described.

2. A trace-lock consisting of a bifurcated section having a concaved inner wall between its members and means for attachment to a whiffle-tree, a pin passed through the members of said bifurcated section, and a button consisting of a shell permanently closed at one end, which permanently-closed end is convexed at its outer surface, the opposite end of the shell being provided with a block which

extends to a point near its center, the shell 15 having slots in opposite sides, which slots receive the pin in the bifurcated section, said pin serving as a pivot for the button, and a spring located within the shell, having bearing against the permanently-closed end there- 20 of and against said pin, as set forth.

In testimony whereof I have signed my name to this specification in the presence of two subscribing witnesses.

THOMAS J. HALSTEAD.
